(57) **CLAIM**

The ornamental design for a tube dispenser, as shown and described.

DESCRIPTION

FIG. 1 is a top and right perspective view of a tube dispenser of the present invention;

FIG. 2 is a left side elevational view of the tube dispenser of FIG. 1;

FIG. 3 is a right side elevational view of the tube dispenser of FIG. 1;

FIG. 4 is a top elevational view of the tube dispenser of FIG. 1;

FIG. 5 is a bottom elevational view of the tube dispenser of FIG. 1;

FIG. 6 is a front end elevational view of the tube dispenser of FIG. 1; and,

FIG. 7 is a rear end elevational view of the tube dispenser of FIG. 1.

The broken lines shown in the drawings are for environmental purposes only and form no part of the claimed design.

1 Claim, 6 Drawing Sheets
